Walter H. Jacobsen, Ivyland, Pa., assignor to The General Plastics Corporation of America, Philadelphia, Pa., a corporation of Pennsylvania

Filed Oct. 8, 1962, Ser. No. 72,021

Term of patent 14 years

(Cl. D54—2)

FIG. 1 is a front elevational view of a trellis embodying my new design.

FIG. 2 is a top plan view of the same.

FIG. 3 is a left hand and elevational view of the same.

FIG. 4 is a right hand and elevational view of the same.

FIG. 5 is a bottom view thereof.

The undisclosed rear of the trellis is the same as the front thereof as shown in FIG. 1.

I claim:

The ornamental design for a trellis, as shown and described.
